(57) **CLAIM**

The ornamental design for a light-emitting diode package, as shown and described.

DESCRIPTION

FIG. 1 is a top perspective view of one embodiment of a light-emitting diode package;

FIG. 2 is a bottom perspective view of the light-emitting diode package of FIG. 1;

FIG. 3 is a top view of the light-emitting diode package of FIG. 1;

FIG. 4 is a bottom view of the light-emitting diode package of FIG. 1;

FIG. 5 is an end view of the light-emitting diode package of FIG. 1;

FIG. 6 is an opposing end view of the light-emitting diode package of FIG. 1;

FIG. 7 is a side view of the light-emitting diode package of FIG. 1;

FIG. 8 is an opposing side view of the light-emitting diode package of FIG. 1;

FIG. 9 is a top perspective view of another embodiment of a light-emitting diode package;

FIG. 10 is a bottom perspective view of the light-emitting diode package of FIG. 9;

FIG. 11 is a top view of the light-emitting diode package of FIG. 9;

FIG. 12 is a bottom view of the light-emitting diode package of FIG. 9;

FIG. 13 is an end view of the light-emitting diode package of FIG. 9;

FIG. 14 is an opposing end view of the light-emitting diode package of FIG. 9;

FIG. 15 is a side view of the light-emitting diode package of FIG. 9; and,

FIG. 16 is an opposing side view of the light-emitting diode package of FIG. 9.

The dashed broken lines shown in the drawings depict portions of the light-emitting diode package that form no part of the claimed design.

(Continued)

The dot-dashed broken lines shown in the drawings depict portions of the light-emitting diode package that represent boundaries of the claimed design and are not part of the claimed design.
